United States Patent Office

Des. 185,578
Patented June 23, 1959

185,578

PAIR OF SUN GOGGLES

Joseph Skelly, Anaheim, Calif.

Application March 12, 1959, Serial No. 54,954

Term of patent 14 years

(Cl. D57—1)

FIG 1

I claim:

The ornamental design for a pair of sun goggles, substantially as shown.
